UNITED STATES PATENT OFFICE

2,160,721

LIGHTING EQUIPMENT

Paul L. Coulter, Santa Monica, Calif.

Application January 18, 1938, Serial No. 185,606

1 Claim. (Cl. 248—205)

This invention relates to improvements in lighting equipment and has particular reference to a lamp which may be employed in several places, such as a book light, a table light, a bed light, or in any other place where illumination is desired.

A further object is to produce a device of this character which is compact, economical to manufacture, light in weight, and neat in appearance.

10 Other objects and advantages will be apparent during the course of the following description.

In the accompanying drawing forming a part of this specification and in which like numerals 15 are employed to designate like parts throughout the same,

Fig. 1 is a side elevation of my device as the same would appear when attached to the back of a book, a portion of the book being broken 20 away;

Fig. 2 is a front elevation of Fig. 1;

Fig. 3 is a top plan view of the lamp used as a stand lamp; and

Fig. 4 is a side elevation of the lamp as employed upon the head of a bed as a bed light.

Applicant is aware of the fact that illuminating means may be employed for a single place, but he is unaware of the fact that a fixture has been devised for use in many places and having the 30 advantages of his lamp.

In the accompanying drawing wherein for the purpose of illustration is shown a preferred embodiment of my invention, the numeral 5 designates a standard having a base portion 6 hinged 35 thereto, to which base portion is pivoted a supporting bar 7. A clip 8 is riveted as at 9 to the upper end of the standard 5 and has an out-turned free end 11. The upper end of the standard 5 is bent whereby an arm 12 may be adjustably secured thereto by a wing nut 13. A reflector 14 is adjustably secured to the arm 12, and

in this reflector an illuminating bulb is positioned. An electric cord is shown at 16. A lug 17 is formed upon the arm 12, the purpose of which will be later seen.

When the device is used upon a book, the clip 5 8 is forced over the back binding of the book so as to lie between the back binding and the stitching of the leaves. In this position, the light will be held directly above the pages, thereby giving the proper illumination.

When the device is used on a lamp stand, the base 6 is moved at right angles with the standard 5, and the supporting bar 7 is then moved at right angles with relation to the base, as shown in Fig. 3.

When the device is used upon a bed, the lug 17 hooks over the bed and thus holds the light in proper position.

It will thus be seen that I have produced a very simple arrangement which will accomplish 20 all the objects above set forth.

It is to be understood that the form of my invention herewith shown and described is to be taken as a preferred example of the same and that various changes relative to the material, 25 size, shape and arrangement of parts may be resorted to without departing from the spirit of the invention or the scope of the subjoined claim.

Having thus described my invention, I claim:

A combination book, bed, and desk lamp embodying in its construction a standard and a base hingedly connected to said standard, a clip pivoted to said standard and adapted to be positioned behind the central binding of a book when the device is used as a book lamp, a bar 35 pivoted to said base and normally lying parallel thereto when the device is utilized as a book lamp and movable at right angles thereto when the device is employed as a desk lamp, and a reflector adjustably secured to said standard. 40

PAUL L. COULTER.
